UNITED STATES PATENT OFFICE.

JAMES WILLIAM DOUGHERTY, OF MCKEESPORT, PENNSYLVANIA.

TOY VEHICLE.

1,420,308.

Specification of Letters Patent. Patented June 20, 1922.

Application filed September 16, 1920. Serial No. 410,667.

To all whom it may concern:

Be it known that I, JAMES WILLIAM DOUGHERTY, a citizen of the United States, residing at McKeesport, in the county of

5 Allegheny and State of Pennsylvania, have invented a new and useful Toy Vehicle, which may be used as a seesaw, a merry-go-round, or a vehicle for children, in which the following is a specification of the same.

10 The object of my invention is to devise a toy vehicle which can be used as a seesaw, a merry-go-round or a vehicle for childish transportation, and to make the toy so that no adjustments are required in order to

15 use any of the aforementioned features; to incorporate features for the safety and convenience of the users of the toy, and whenever possible to garb these features with attractive configurations which will appeal

20 to children. When this toy is being used, the up and down motion of the see-saw, the revolving motion of the merry-go-round together with the motion necessary to transport from one point to another being im-

25 parted to it by the feet of the users of this toy vehicle.

I attain these objects by the mechanism illustrated in the accompanying drawings in which—

30 Fig. 1 is a side view of the toy, the up and down or see-saw motion being indicated by the full and dotted line arrangement, the animal heads being omitted in the dotted outline for clearness.

35 Fig. 2 is an end view of the toy.

Fig. 3 is a top view, the dotted parts indicating the change in position as the toy revolves in a horizontal plane.

Similar numerals will refer to similar 40 parts throughout the several views.

In the figures, the numeral 1 refers to the balancing wheels which are revolvably fitted on the axle 2, which is secured to the bridge 3. Secured to the bridge 3 is the balancing 45 board 4 and the stiffening blocks 5. Mounted on the balancing board 4 at an equal distance from the axis of balancing wheels 1, are the animal heads 6 having the hand gripping handles 7 which the child may grip when riding on this toy. Secured to

50 the ends of balancing board 4 are the back boards 8 forming the seats 9 for the user of the toy. Secured to the back board 8 and the balancing board 4 are the blocks 10 with 55 the caster wheels 11 fitted thereto; when the caster wheels are in contact with the floor

they automatically adjust themselves to the direction of motion of the toy, and they are also fixed at a distance from the floor to limit the see-saw motion of the balance-board 4 as shown in Fig. 1. The drawings show a single caster wheel at each end of the toy, on the larger sizes and on some of the smaller sizes of this toy I employ two casters for the purpose of obtaining greater durability and stability. Some of my designs of this toy are entirely of wood, whilst others are made up of wood and steel, the cost and adaptability being the factors which determine the material used.

To use this toy the children seat themselves at 9, with their backs against the boards 8, and grip the handle 7 using their feet to see-saw up and down and whirl themselves around after the manner of a merry-go-round or to transport themselves from one point to another.

Before making my claims I desire to point out the particular features of my invention which make valuable and desirable as a toy vehicle.

1st. I have combined a see-saw and a merry-go-round in a movable wheeled toy vehicle, this feature of having the see-saw and merry-go-round mounted on wheels and 85 movable therewith enables the small children who use this toy to push or pull it from one place of play to another with a very small effort. It also can be used as a vehicle for coasting down grades and for 90 childish transportation.

2nd. I have incorporated caster wheels into the vehicle feature of my invention, these caster wheels automatically adjust themselves to the direction the toy moves 95 without any attention from the user of the toy.

3rd. As a safety measure, and for ease and convenience when using this toy I have incorporated back boards in connection with 100 the balancing board to form seats thereon and gripping handles to prevent the children from being thrown off this toy when it is in motion. These features I wish to protect and desire to secure Letters Patent 105 covering them in the following claims.

I claim:

1. A toy vehicle of the kind described, comprising a balancing board, back boards secured to each end of said balancing board 110 to form seats thereon, figure heads mounted on said balancing board in proximity to said

seats, handles secured to said figure heads, a support rigidly secured to said balancing board near its middle, wheels fitted to said support to permit a see-saw, a revolving or a 5 rectilinear motion of said balancing board, a part secured to each end of balancing board to limit the see-saw motion thereof, caster wheels secured to said part to facilitate the revolving and the rectilinear motion 10 of said balancing board.

2. A movable wheeled toy vehicle consisting of the combination of a balancing board to form a body, back boards secured to the ends of balancing board to form seats there- 15 on, figure heads having hand gripping handles mounted on said balancing board in proximity to said seats, a pair of wheels revolvably fitted to an axle which is secured to and supports the balancing board near its 20 middle, said wheels being arranged to permit a revolving, a straight line or a see-saw motion of the balancing board, caster wheels secured to and supporting the ends of the balancing board, said caster wheels when 25 in contact with the floor automatically adjust themselves to the direction of motion of the ends of the balancing board and are positioned to permit a see-saw motion of balancing board about the axis of the wheels near 30 its middle, substantially as described.

3. A movable wheeled toy vehicle consisting of the combination of a balancing board to form a body, back boards secured to the ends of balancing board to form seats there- 35 on, a pair of wheels revolvably fitted to an axle which is secured to and supports the balancing board near its middle, said wheels

being arranged to permit a revolving, a straight line or a see-saw motion of the balancing board, caster wheels secured to and supporting the ends of the balancing board, said caster wheels when in contact with the floor automatically adjust themselves to the direction of motion of the ends of balancing board and are positioned to permit a see-saw 40 motion of the balancing board about the axis of the wheels near its middle, substantially as described. 45

4. A movable wheeled toy vehicle consisting of the combination of balancing board to form a body, back boards secured to the ends of balancing board to form seats there- 50 on, a pair of wheels revolvably fitted to an axle which is secured to and supporting the balancing board near its middle, said wheels 55 being arranged to permit a revolving and a straight line motion of the balancing board, caster wheels secured to and supporting the ends of the balancing board, said caster wheels when in contact with the floor automatically adjust themselves to the direction of motion of the ends of balancing board and are positioned to permit a see-saw motion 60 of the balancing board about the axis of the wheels near its middle, substantially as de- 65 scribed.

In testimony whereof I have signed my name to this specification and claims, in the presence of two subscribing witnesses.

JAMES WILLIAM DOUGHERTY.
